(57) **CLAIM**

The ornamental design for a table, as shown and described.

DESCRIPTION

FIG. 1 is an end side perspective view of a table showing my new design;

FIG. 2 is a side elevational view, the opposite side being a mirror image thereof;

FIG. 3 is an end elevational view, the opposite end being a mirror image thereof; and,

FIG. 4 is a top view thereof.

"The fragmentary depiction of the surface pattern on the sides of the article is understood to exist uniformly across those surfaces."

The bottom view of the table is not shown and forms no part of the claimed design.
